UNITED STATES PATENT OFFICE.

GEORGE H. CONNERS, OF HARTFORD, CONNECTICUT.

ADVERTISING APPARATUS.

Application filed December 13, 1927. Serial No. 239,674.

This invention relates to an apparatus which is more particularly designed for billboard and sign advertising.

The object of the invention is to provide a simple apparatus which may be readily attached to a billboard or sign that carries advertising matter in which the representation of the emission of smoke is a feature to be depicted for producing the smoke.

10 This object is attained in the present instance by attaching a chamber containing an electrically heated resistance or hot plate to the back of the billboard or sign and leading a pipe from the chamber to an opening 15 in the billboard or sign at the locality where it is desired that smoke shall be emitted, a pipe from a reservoir or cup containing oil being led into the chamber over the hot plate or resistance so that oil may 20 be dropped therefrom onto and be vaporized by the resistance or hot plate that is connected in a circuit which is closed by an electrically operated time switch that is also arranged to control the discharge outlet 25 from the oil reservoir or cup, whereby the time switch may be set to simultaneously cause the resistance or hot plate to become heated and the oil to drop thereon, at a definite time for a predetermined period, and 30 then coincidentally shut off the current from the resistance or hot plate and stop the flow of oil.

In the accompanying drawings Fig. 1 is a representation of a billboard provided with 35 an apparatus that embodies this invention. Fig. 2 is a view of the apparatus on larger scale and with parts in section.

The chamber 1 may be attached to the back 40 of the billboard 2 by any suitable means and the pipe 3 is led from the top of the chamber to the locality where the smoke is to issue, which in the case illustrated is represented as the bowl of a smoking pipe 4. Near the bottom of the chamber openings 5 are made to permit the entrance of 45 the necessary amount of air to promote vaporization of the constituents of the oil that are to make the smoke, and to ensure the necessary upward draught of heated air 50 which will carry the smoke to the outlet up on the billboard. Fastened to but insulated from the bottom inside of the chamber is a resistance plate 6 on which is a cup 7. Connected with this plate by binding screws 8 55 are wires 9 and 10 that lead from a time switch 11. This switch may be any of the

common well known types of electrically operated switches such as are used for street lighting, signs, billboards, and store windows for automatically turning on and off 60 current at predetermined times.

Extending on an incline into the chamber and having its lower end opening above the cup 7 is a tube 12. The upper end of this tube is attached to the outlet end of an oil 65 reservoir or cup 13 of common construction. The switch spindle 14 of the time switch is extended through the switch casing and on the end of this spindle and fastened to it so as to turn with the switch in the usual 70 manner is a cam 15. The oil cup is located adjacent to the time switch in such position that this cam engages the head of the valve spindle 16 of the oil cup and forces the valve spindle down when the cam is turned to 75 one position and allows the valve rod to be raised by the spring 17 when the cam is turned over as the switch is thrown.

By the apparatus described, according to 80 the setting of the time switch, the circuit to the hot plate is closed and opened and coincidentally the outlet valve of the oil cup is opened and closed so that oil will trickle down the tube and drop onto the heated hot plate, which action continues until the setting of the time switch turns off the current 85 and closes the oil cup valve. When oil drops in this manner upon the hot plate smoky vapor is produced and this smoke is carried up by the draught caused by the 90 heated air, through the pipe to the outlet on the billboard or sign where it issues with realistic effect.

The invention claimed is:

1. An apparatus for use in connection 95 with advertising signs which comprises a chamber having an outlet adapted to open through the sign, electrically heated means in said chamber, an oil receptacle with its discharge leading into the chamber above said electrically heated means, and a time switch, said time switch having means which coincidentally controls an electric circuit that includes the electrically heated means within the chamber and the discharge from the 100 oil receptacle.

2. An apparatus for use in connection 105 with advertising signs which comprises a chamber having an outlet pipe adapted to be extended to an opening through the sign, electrically heated means in said chamber, an oil receptacle having a discharge pipe 110

- leading on an incline into the chamber above said electrically heated means, and a time switch, said time switch having means which coincidentally controls an electric circuit that includes the electrically heated means within the chamber and the discharge from the oil receptacle.
3. An apparatus for use in connection with advertising signs which comprises a chamber having air intake openings near its lower end and an outlet pipe extending upward to an opening in the sign, electrically heated means in the lower part of said chamber, an oil receptacle having a discharge pipe leading on an incline into the chamber above said electrically heated means, and a time switch, said time switch having means which coincidentally controls an electric circuit that includes the electrically heated means within the chamber and the discharge from the oil receptacle.
4. An apparatus for use in connection with advertising signs which comprises a chamber having an outlet adapted to open through the sign, electrically heated means

in said chamber, an oil receptacle with its discharge leading into the chamber above said electrically heated means, and a time switch, said time switch having a switch which controls an electric circuit that includes the electrically heated means within the chamber and having a cam which controls the discharge from the oil receptacle, said controlling means operating coincidentally.

5. The combination with an advertising sign of a chamber attached to the sign and having an outlet adapted to open through the sign, electrically heated means in said chamber, an oil receptacle adjacent to said chamber and having its discharge leading on an incline into the chamber above said electrically heated means, and a time switch, said time switch having means which coincidentally controls an electric circuit that includes the electrically heated means within the chamber and the discharge from the oil receptacle.

GEORGE H. CONNERS.
